UNITED STATES PATENT OFFICE.

THOMAS F. MALONEY, OF NEW YORK, N. Y.

BELT-BUCKLE.

1,073,504.

Specification of Letters Patent. Patented Sept. 16, 1913.

Application filed May 23, 1912. Serial No. 699,211.

To all whom it may concern:

Be it known that I, THOMAS F. MALONEY, a citizen of the United States, and a resident of the city of New York, borough of the Bronx, in the county and State of New York, have invented a new and Improved Belt-Buckle, of which the following is a full, clear, and exact description.

This invention relates to buckles, and particularly to belt buckles, and has for an object to provide an improved structure in which a sliding cam action is utilized for clamping the buckle in place.

Another object in view is to provide a buckle with a turned over edge arranged at an angle to the general direction of the body so as to provide inclined ways or cams against which a clamping plate acts when the buckle is being secured in place so as to firmly clamp the buckle in position regardless of the thickness of the belt or strip of material on which it is placed.

In carrying out the objects of the invention, a simple structure is produced in which a base or body portion is provided, having sides extending at substantially right angles thereto for presenting a channel-shaped structure in cross section. The sides or channels are inclined from the body portion and turned over on one edge so as to provide inclined or cam ways in which a clamping plate is adapted to move, whereby a belt or other article may be clamped rigidly in place.

35 A practical embodiment of the invention is represented in the accompanying drawings forming a part of this specification, in which similar characters of reference indicate corresponding parts in all the views.

40 Figure 1 is a front elevation of an embodiment of the invention shown applied to a belt; Fig. 2 is a section through Fig. 1, on the line 2—2; Fig. 3 is a rear view of the structure shown in Fig. 1; Fig. 4 is a section through Fig. 2 on the line 4—4; Fig. 5 is a side view of the buckle removed; and Fig. 6 is a longitudinal vertical section through the buckle shown in Fig. 5.

45 Referring to the accompanying drawings by numerals, 1 indicates a belt of any desired kind, in which the end 2 is threaded through the buckle 3 and clamped in position by the clamping plate 4 of the buckle. The clamping plate 4 is provided with hand-operated members 5 and 6 for moving the plate back

and forth in order to cause a proper initial engagement of the clamping plate with the belt. The buckle 3 is formed with a face plate or portion 7 having sides 8 and 9 extending to the rear therefrom. Each of the sides 8 and 9 is comparatively large at the end 10 and comparatively narrow at the end 11, the outer edges of the sides forming a substantially arc-shaped line 12. The curve of line 12 diverges from the curve of the front of the face plate 7, as clearly shown in Figs. 5 and 6. Each of the sides 8 and 9 is normal to the plate 7 and their longitudinal edges are bent over and clamped against the sides for forming projections or shoulders 13 and 14 against which the ends 15 and 16 press when the clamping plate is being moved to a clamping position. In bending over the members 13 and 14, the same are preferably bent over the same distance for their full length from end 10 to end 11, whereby an inclined way or cam is formed against which the plate 4 acts. The plate 4 is formed with a biting edge 17 and a turned up end 18, whereby the end 2 of the strap may be easily inserted and after plate 4 has been moved manually to a clamping position the rearward movement of the end 2 will merely cause a tighter clamping of the clamping plate, as the same is caused to move down the turned over portions or inclined ways 13 and 14. As clearly shown in Figs. 2 and 3, the sides 8 and 9 are provided with a bracing member or portion 19 extending transversely of the body and formed integrally therewith. This bracing portion or member 19 is arranged at the ends of the sides 8 and 9 and not only braces the sides, but acts as a bar over which the strap 1 may be looped. From this construction it will be noted that by moving the clamping plate 4 toward the end 10 which is the large end, the clamping plate will be loosened and the end 2 may be freely inserted and removed. When the clamping plate 4 is moved to the opposite end or toward end 11, the strap 1 will be firmly clamped in place and any pulling or tendency to pull the strap from the end of the buckle will merely cause the clamping plate to slide down the ways 13 and 14 and more firmly clamp the strap in position. It will thus be seen that the clamping action of the plate is caused by the arrangement of the ways 13 and 14

in opposition to the face plate 7 and that the ways together with the clamping plate utilize the cam or wedge principle.

The formation of the shoulders 13 and 14, 5 by bending them over and clamping them against the sides 8 and 9, makes said shoulders very strong and prevents the opening of same by the clamping plate 4 when wedging the belt against the plate 7.

10 In my buckle the clamping plate may be removed through the end 11 when the belt is removed from the buckle, as, for example, to repair the plate 4 when it is necessary, or to change the plate 4 for another belt of 15 a different thickness.

Having thus described my invention I claim as new and desire to secure by Letters Patent:—

20 1. In a buckle of the class described, a body portion having sides normal to the same and gradually increasing in width from one end of the body to the other; a bracing portion integral with said sides at their widest end, said sides having their 25 longitudinal edges turned toward said body and clamped against said sides, thereby forming a passageway which increases in width toward said bracing portion; and a loosely mounted clamping plate in said passageway bearing against said turned, 30 clamped edges and adapted to reciprocate

in said passageway between said sides, said plate having means overhanging said sides whereby said plate may be made to reciprocate.

35

2. In a buckle of the class described, a body portion having sides normal to the same and gradually increasing in width from one end of said body to the other end; a bracing portion extending transversely of 40 said body integral with said sides at their widest end, thereby forming a loop for a belt at one end of said body, said sides having their longitudinal edges turned toward said body and clamped against said sides, 45 thereby forming a passageway which gradually increases in width toward said bracing portion; and a slidably, loosely and removably mounted clamping plate in said passageway bearing against said turned clamping edges, and having means overhanging said sides of said body whereby said plate may be made to reciprocate in said passageway of said body.

50

In testimony whereof I have signed my name to this specification in the presence of two subscribing witnesses.

THOMAS F. MALONEY.
